COIN CHUTE

Walter A. Tratsch and Bernhard C. Grunig,
Chicago, Ill.

Application October 2, 1935, Serial No. 43,152

2 Claims. (Cl. 194—97)

This invention relates to a coin chute.

It is an object of this invention to provide an improved coin chute which is relatively simple and inexpensive in construction and efficient in use.

Another object of the present invention is to provide an improvement upon the visible display coin chute shown and described in our copending application, Serial No. 11,103, filed March 10 14, 1935.

A further object of the present invention is to provide a fraud-prevention attachment for the coin chute shown and described in our above-identified copending application and by means of which the operator of the coin chute is prevented from inserting a wire or analogous tool through the coin chute into engagement with the coin controlled mechanism with which the coin chute is associated.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a top plan view of a coin chute embodying a preferred form of the present invention;

Fig. 2 is a longitudinal vertical sectional view of the same on line 2—2 in Fig. 1;

Fig. 3 is a fragmentary bottom plan view, on line 3—3 in Fig. 2, showing the new fraud-prevention attachment and showing a fraudulent instrument in the form of a wire in ineffective position; and

Fig. 4 is a transverse sectional view on line 4—4 in Fig. 2.

The coin chute shown in the accompanying drawing is substantially the same as the coin chute which is described and claimed in our above-identified copending application, except for the fraud prevention attachment which forms the subject matter of this application, the said coin chute being generally indicated at 10, and comprising a guide structure 11, and a coin slide 12 carried thereby; the said coin slide 12 being provided with a coin aperture 24, and the guide structure 11 including a mounting or face plate 35 by means of which the coin chute 10 may be mounted in the wall of the cabinet or casing of a coin-controlled device, machine or apparatus, as is well understood in the art.

The coin chute 10 is provided with the usual fraud-prevention devices for preventing the use

of fraudulent or spurious coins, such fraud-prevention devices being generally indicated at 20 and being of the type disclosed in the Tratsch and Hall patents, No. 1,908,380, granted May 9, 1933, and No. 1,908,752, granted May 16, 1933.

Provided in the coin slide 12 is an elongated slot 21 (Fig. 1) and projecting into this slot 21 is an upwardly projecting pin or stud 22 which is carried by a slide 18, this slide 18 being slidably mounted upon the bottom wall 23 of the guide structure 11 and below the slide 12. Provided in the slide 18 is a coin aperture 19.

Mounted on, or formed as a part of the upper wall of the guide structure 11, as may be desired, 15 is an annular member or ring 13 in which is provided a coin displaying sight opening 14 and formed in a horizontal wall 16 of the guide structure 11, below the coin slide 12, is a coin display pocket 17 (Fig. 2), this display pocket 17 being 20 disposed in registration with the sight opening 14.

Having one end attached to the slide bar 18, as at 25, and having its other end attached to the bottom wall 23 of the guide structure 11, as at 26, is a resetting spring 27 by means of which 25 the slide bar 18 is normally urged (right to left, Figs. 1, 2, and 3) so as to dispose the coin aperture 19 therein in registration with the sight opening 14 and the coin display pocket 17; the slide bar 18 being stopped in this position in 30 any suitable manner, as by the means shown for this purpose in our above-identified copending application.

Provided in the coin slide 12 is a sight opening 28 and the coin slide 12 is normally urged (right 35 to left, Figs. 1 and 2) by its resetting spring 27, so as to dispose the sight opening 28 which is formed therein (Figs. 1 and 2) in registration with the coin display or sight opening 14 which is formed in or upon the top wall of the guide structure 11.

Formed as a part of the annular member or ring 13, or attached thereto in any suitable manner, as may be desired, is an extension 31 and this extension 31 has a depending flange 32, this flange 32 45 extending around a part of the marginal edge of the plate or extension 31 (Figs. 2, 3, and 4) and bearing at its lower edge against the upper surface of the slide 12, it being noted that the depending flange 32 extends transversely across the slot 21 50 and between the sight opening 28 and the inner end of the slide 12 when the latter is in its normal position (as in Fig. 2).

Provided in the upper surface of the shelf 16 (Fig. 2) is a depressed ledge or pocket 29. 55

Operation

The coin slide 12 is normally disposed, by the action of its resetting spring 30, in coin-receiving position with the sight opening 28 which is formed in the coin slide 12 disposed in registration with the sight opening 14, as shown in Fig. 2, and when a coin is inserted into the coin aperture 24 of the coin slide 12 and the latter is pushed inwardly (left to right, Figs. 1 and 2) the coin or token disposed in the coin aperture 24 of the slide 12 is carried by the slide 12 along the upper surface of the bottom wall 33 of the guide structure 11, and falls from the latter into the pocket 29 which is formed as a depressed ledge in the guide structure 11, whereupon further inward movement of the coin slide 12 causes the coin or token which is disposed in the coin aperture 24 of the coin slide 12, and in the pocket 29, to be angled downwardly off the front or inner end of the pocket 29, and further inward movement of the coin slide 12 urges the coin or token into the sight opening or pocket 11 whence it falls onto the upper surface of the rear portion of the slide bar 18.

The coin or token is thus deposited in the display pockets 14-17, upon the upper surface of the slide bar 18, and as the coin slide 12 is pushed inwardly (left to right, Figs. 1 and 2), the end wall of the slot 21, which is formed in the coin slide 12, engages the pin 22, which is carried by the slide 18, whereupon the slide 12 and the slide 18 move together as a unit (left to right, Figs. 1 and 2), and when the slides 12 and 18 are returned to their normal or initial positions the coin or token which has previously been deposited on the upper surface of the lower slide 18, drops into the pocket or opening 19, wherein it is exposed to view through the registered sight openings 14, 17, and 28.

The present invention is particularly concerned, as has been set forth hereinbefore in the statement of the objects of the present invention, with the provision of means (the flanged plate 31-32) whereby the operator of the present coin chute will be prevented from inserting a wire or analogous fraudulent instrument 34 through the coin aperture 24 of the slide 12 and thence through the body of the coin chute, by way of the elongated slot 21 and the sight opening 28, as indicated in dotted lines (Fig. 2),—it being understood that when a wire or other like fraudulent instrument is thus inserted through the coin chute shown and described in our said copending application its inner end may be engaged with the operating mechanism of the apparatus with which the coin chute is associated and the said apparatus may thus be fraudulently operated without the insertion of a proper coin into the coin aperture of the slide and by less than a full stroke of the latter.

This was a difficulty experienced in the use of the coin chute shown and described in our above identified copending application and in the use of the present coin chute this difficulty is overcome by the provision of the flanged plate 31-32, since when a fraudulent instrument 34 is inserted into the present coin chute, by way of the coin aperture 24 and the slot 21 in the slide 12, its inner end will abut the depending flange 32 of the plate 31 and the said instrument will thus be

prevented thereby from being moved past the flange 32 into engagement with the operating mechanism 40, for example, of the apparatus with which the coin chute is associated, that is, the wire or like fraudulent instrument 34 will be prevented from being moved into its effective position to move the slide member 40, associated with the game board 42, to the dotted-line position (Fig. 2), it being understood that the fraudulent instrument 34 may be inserted, as shown, into the coin chute shown in our said copending application and which does not embody the flanged plate 31-32.

While the fraud-prevention attachment 31-32 has been described and illustrated as associated with the visible display coin chute shown and described in our said copending application it may be used with other types of coin chutes which have a slot such as the slot 21, for the reception of a stop for a magnetic disc, as in the Tratsch 20 and Hall patents, Nos. 1,908,380 and 1,908,752, or which have a slot such as the slot 21 for the reception of any other device or instrumentality, and through which a wire or like fraudulent instrument may be projected after being inserted 25 into the coin aperture of the slide.

While we have illustrated and described the preferred form of construction for carrying our invention into effect, this is capable of variation and modification, without departing from the 30 spirit of the invention. We, therefore, do not wish to be limited to the precise details of construction set forth, but desire to avail ourselves of such variations and modifications as come within the scope of the appended claims.

Having thus described our invention, what we claim as new and desire to protect by Letters Patent is:

1. A coin chute comprising a guide structure; a slide carried by the said guide structure provided 40 with a coin aperture and having an elongated slot formed therein and extending axially relative to the long axis and plane of movement of said slide for the reception of a stop for a magnetic disc or other fraud-prevention instrumentality; a member carried by the said guide structure above the said slide and having a flange depending therefrom extending transversely across said slot and into engagement with the upper surface of said slide so as to prevent a wire or other 50 analogous or like instrument from being projected through the body of said coin chute by way of said coin aperture and said slot.

2. A coin chute comprising a guide structure; a slide carried by the said guide structure provided with a coin aperture and having an elongated slot formed therein in communication with said coin aperture and extending axially relative to the long axis and plane of movement of said slide for the reception of a fraud-prevention instrumentality; a member carried by the said guide structure above the said slide and having an edge or lip extending transversely across said slot and bearing against the upper surface of said slide so as to prevent a wire or other analogous or like instrument from being projected through the body of said coin chute by way of said coin aperture and said slot.
